VARIABLE REACTANCE AND CONTROL
CIRCUIT THEREFORMurray G. Crosby, Riverhead, N. Y., assignor to
Radio Corporation of America, a corporation
of Delaware

Application December 31, 1941, Serial No. 425,022

3 Claims. (Cl. 179—171.5)

This application concerns a variable condenser, which may be used for automatic frequency control and frequency modulation purposes, wherein a piezo-electric bending or twisting unit is the condenser actuating element. The device provides a simple and compact means of frequency modulating an oscillator or phase modulating a tuned circuit. It is especially suitable for automatic frequency controlling the high frequency oscillator of an U.-H.-F. receiver since it requires little or no power for operation and since the reactance tubes usually used for such purposes are relatively insensitive at the ultra high frequencies.

In describing my invention more in detail, reference will be made to the attached drawings wherein,

Figs. 1a and 1b illustrate a piezo-electric crystal unit arranged in such a manner as to bend when excited by variable potentials as shown.

In Fig. 1c is shown, rather schematically, a crystal unit of the type illustrated in Figs. 1a and 1b, cooperating with elements of a reactance such as a condenser to provide a variable reactive effect.

Fig. 1d illustrates a modification of the arrangement of Fig. 1c.

Figs. 2 and 3 illustrate high frequency circuits associated with the variable reactance of the prior figures. In Fig. 2 the variable reactance is used to control in a novel manner an oscillator in a receiver while in Fig. 3 the variable reactance is shown connected in a novel manner with the generator of a transmitter to control the frequency thereof.

Fig. 1a shows a section of the type of crystal bending unit used here to provide variable capacity. Crystals 6 and 8 are cemented or otherwise bound together and associated with plates 10, 12, and 14, of which plate 14 is between the crystal sections. The crystal axes are so oriented that when voltage is applied to terminals 10 and 12 and thence differentially to the crystal segments, one of the crystals is compressed in its lengthwise dimension and the other is elongated. This causes the unit to operate like a bi-metallic thermal element so that when voltages are applied to the terminals 10 and 12 the unit bends as shown in Fig. 1b.

Composite crystal units of the nature involved here, in which Rochelle salt crystals are used, are described in an article by C. Baldwin Sawyer, entitled "The use of rochelle salt crystals for electrical reproducers and microphones," pub-

lished in the Proceedings of the I. R. E. for November, 1931.

Figs. 1c and 1d show methods of utilizing this bending movement of the crystal unit to form a variable capacity which varies in proportion to the voltage applied to the crystal electrodes. In Fig. 1c the crystal 20, which may be made up of two sections arranged and excited as described above in connection with Fig. 1a, is clamped to holder 18 by means of bar 22 and screw 24. The bottom of electrode 19 on the crystal acts as one plate of the condenser and plate 26 acts as the other plate. A dielectric 28, which may consist of mica or a similar material, may be placed between the condenser plates if desired. The clamping of the crystal unit is adjusted so as to leave an air gap at the free end of the crystal for the normal position of the condenser without voltage applied. Then, as voltage is applied by leads 30 and 32 to the crystal electrodes, the bending movement of the crystal either increases or decreases the spacing between the condenser plates 19 and 26 and thereby decreases or increases the capacity. The variable capacity may be used by connections 34 and 36 of which 36 is grounded as is plate 19.

Fig. 1d shows an arrangement in which the crystal bending unit operates a compression type condenser. The condenser consists of a flat plate 40, a dielectric such as mica 42, and a curved plate 44. The curved plate without pressure allows an air gap to exist between the plate and the dielectric. When voltage is applied to terminals 46 and 48 to cause crystal unit 50 to bend, the end of the bending unit presses down on the curved condenser plate 44 through an insulating material such as rubber 52. By means of the two clamps 54 and 56, with their screws 58 and 60 cooperating with support 61 on holder 59, the free end of the crystal may be moved up and down to adjust the normal position of the condenser. Application of voltage to terminals 46 and 48 then causes the bending unit to vary the degree of compression in the compression type condenser and consequently vary the capacity. Connection to the condenser plates is afforded by terminals 62 and 64.

The controllable reactance described above may be put to wide use in the radio art. For example, the controllable reactance may be used to tune an alternating current circuit of any type such as, for example, a circuit wherein alternating current to be phase modulated flows, or an oscillation generator circuit the frequency of which is to be modulated by the control potentials ap-

plied to the piezo-electric crystal unit to provide frequency modulation in a modulator system or to provide automatic frequency control of an oscillator in a receiver, etc.

Fig. 2 shows how such a type of variable condenser may be used for automatic frequency control. Tuned circuits 70, 72, and 74 are the discriminator of a frequency modulation receiver or of an automatic frequency control system of any type of receiver illustrated diagrammatically by box 78. This receiver includes in 76 a mixer tube supplied by oscillations from generator tube 73 and an intermediate frequency amplifier feeding tube 75. Normally, tuned circuit 72 might be tuned above the mean intermediate frequency and tuned circuit 74 below the mean frequency while the primary tuned circuit 70 might be tuned to approximately the mean frequency. The tuned circuits are damped by resistors 76, 77, and 78 to cause the discriminator to have the proper band width. Detectors 80 and 82 detect the amplitude modulations from the discriminator so that modulation output, where 78 is a frequency modulation receiver, and automatic frequency control potentials appear across resistors 84 and 86. The automatic frequency control potentials are fed through resistor 88 and chokes 90 and 92 to the electrodes of crystal element 20. Resistance 88 and condenser 89 form a time constant circuit which removes the fast variations and allows the slow variations characteristic of slow changes in the mean frequency of the received wave energy to pass to the piezo-electric bending unit. The type of variable condenser shown here is similar to the one of Fig. 1c. Crystal electrodes or plates 20 and 19 are connected to the chokes 90 and 92. Plate 20 acts as one plate of the condenser and the bottom electrode 19 of the crystal acts as the other plate. The crystal is clamped by means of bars 22 and 18 as shown in Fig. 1c. 91 is an insulating separator. Connection is made to the tuned circuit 94 of oscillator 73 through condenser 89 and lead 98. Voltage from this oscillator is fed to the mixer tube via lead 100. This oscillator may be the high frequency oscillator of a superheterodyne or the second oscillator of a double intermediate frequency superheterodyne. Chokes 88 and 92, in connection with condenser 89 and resistance 88, act as a filter to isolate the oscillator circuit 94 from the detector circuit 70, 72, etc.

Fig. 3 shows an application of the piezo-electric variable condenser to a frequency modulator for the production of frequency modulated waves. In Fig. 3, tube 104 oscillates because tuned circuit 106, 108 couples its grid 107, cathode 109 and anode 111 in a regenerative circuit of the Hartley type. The piezo-electric variable condenser

110 forms a part of the variable capacity of the tuned circuit since its one electrode 115 is connected to one terminal of inductance 108 and its other electrode 116 is connected to ground. Modulation input is applied to jack 112 through isolating filter 114, 116 to operate the variable condenser. This filter prevents high frequency energy from reaching the modulation circuits. Output from the oscillator circuit is fed to unit 118 which contains frequency multipliers, limiters, and power amplifiers. The output of unit 118 may be applied to an antenna or other transmission medium.

While I have shown my novel variable reactance in an oscillation generating circuit for control and modulation purposes it will be understood that the same may be used in a tuned circuit of any type such as, for example, one in which wave energy of carrier wave frequency to be modulated in phase flows.

It will be understood that the torque units described in the above mentioned article by C. B. Sawyer may be used as the actuating element in a manner similar to the use of the bending units.

25 What is claimed is:

1. A reactance including, a composite piezo-electric crystal comprising adjacent sections the axes of which are at angles with respect to each other, whereby the sections change in form in different directions when the composite crystal is excited to produce resultant movement, and a reactance element mechanically connected to said crystal.
2. A capacitive reactance including, a composite piezo-electric crystal comprising adjacent sections the axes of which are at angles with respect to each other, whereby the sections change in form in different directions when the composite crystal is excited to provide resultant movement, and a condenser element mechanically linked to said crystal.
3. In a wave length modulation system, an oscillation generator including an electron discharge device having electrodes connected in oscillation generating circuits, a composite piezo-electric crystal comprising two sections the axes of which are at angles with respect to each other, whereby the sections change in form in different directions when the composite crystal is excited, a reactive element mechanically connected to said composite crystal and included in said oscillation generating circuit to determine in part the frequency of the oscillations generated, and means for applying a control potential to points on said crystal to cause relative movement of the sections thereof and thereby movement of said reactance element.
